Primary Examiner—A. Hugo Word*Assistant Examiner*—Doris Clark*Attorney, Agent, or Firm*—James D. Hall**[57] CLAIM**

The ornamental design for a door sill extrusion, as shown and described.

DESCRIPTION

FIG. 1 is a top perspective view of a door still extrusion showing our new design, the extrusion being broken in the center to indicate indeterminate length; and, FIG. 2 is a bottom perspective view thereof.

FIG. 1

FIG. 2
